UNITED STATES PATENT OFFICE

2,221,575

CIRCUIT INTERRUPTER

Earl K. Clark, Mansfield, Ohio, assignor to Westinghouse Electric & Manufacturing Company, East Pittsburgh, Pa., a corporation of Pennsylvania

Application August 3, 1938, Serial No. 222,800

3 Claims. (Cl. 200—153)

My invention relates to a circuit interrupter, and more particularly to a relatively thin switch for use in domestic appliances and the like.

With the modern trend in styling of appliances, such as sandwich grills and coffee makers, it has been practically impossible to adapt present control switches to the particular structures thereof in view of the physical dimensions of such switches. The mere reduction in size of the switches, while maintaining sufficient current-carrying capacity thereof, resulted in inefficient structures, the parts of which would bind or become generally inoperative with repeated operations.

It is, therefore, an object of my invention to provide a thin, compact appliance switch capable of handling at least 1300 watts, without the co-operating parts thereof binding after repeated operations in the field.

Another object of my invention is to provide a thin, compact appliance switch having an operating arm operating in one plane which is capable of moving a contact in a plane normal to such control arm without any binding action therebetween.

A further object of my invention is to provide an efficient, rugged, inexpensive, compact, thin appliance switch which has a positive contact pressure.

Other objects of my invention will either be pointed out specifically in the course of the following description of a device embodying my invention, or will be apparent from such description.

In the accompanying drawing,

Figure 1 is a perspective view of a device embodying my invention in its open position,

Fig. 2 is an end view of the operating lever,

Fig. 3 is a view similar to Fig. 1 showing the device in its closed position,

Fig. 4 is a side elevational view of the device shown in Fig. 1, and;

Fig. 5 is a perspective view of the resilient contact supporting member.

Referring to the accompanying drawing, I show a thin appliance switch 10 comprising a base or supporting structure 12, a manually operable operating lever 14, a resilient contact supporting member 16 associated therewith, a movable contact 18 rigidly attached to member 16, 50 stationary contacts 20 mounted on the base, a contact operating pin 22 on member 16 and a fulcrum-supporting pin 24 for attaching the operating lever 14 and resilient member 16 to the supporting structure.

The supporting structure 12 is preferably formed

from a strip of sheet metal, and has a base 25 and a relatively short upwardly extending flange 26 located at one end thereof. A slotted aperture 28 is located in the flange 26 substantially at its junction with the base 25 to permit the operating lever 14 to extend therethrough, as herein-after described. A notch 30 is positioned in the upper edge of the flange 26 substantially at the midpoint thereof. The notch 30 is substantially as long as the width of the resilient contact supporting member 16 so as to receive such member and to prevent horizontal movement thereof, substantially as herein-after described. However, it is to be understood that the base 12 may be formed in any other manner which permits the co-operative action of the operating handle 14 and resilient contact supporting member 16 substantially as herein-after described.

The operating lever 14 comprises a handle portion 32 and a fan-shaped portion 34. The operating lever 14 is swingably attached intermediate the ends thereof, preferably near the apex of fan-shaped portion 34, to the base 25 of the supporting structure 12 by means of a fulcrum pin 24, substantially as herein-after described. The operating handle portion 32 extends, substantially parallel to the base 25, through the aperture 28 in the flange 26, whereas the fan-shaped portion 34 is located substantially parallel to the base 25 and is positioned over such base to cooperate with operating pin 22, as herein-after described. It, therefore, follows that as the handle portion 32 of the operating lever 14 is moved in a plane substantially parallel to the base 25, the operating lever 14 will be rotated about the fulcrum supporting pin 24 and the fan-shaped portion 34 of the lever 14 will likewise be moved in a plane parallel to the base 25.

An upwardly extending tapered flange portion or ledge 35 is positioned along a portion of the outer edge of the fan-shaped portion 34 of the operating lever 14, see Figs. 1 and 3. The flange-shaped portion or ledge 35 tapers upwardly from substantially the midpoint of the outer edge of the flat fan-shaped portion 34 and along the edge of the fan-shaped portion 34, and cooperates with the contact operating pin 22 so as to move it substantially normally to the base 25 with the rotative movements of handle 14, as herein-after described.

The resilient contact supporting member 16 is, in this instance, a long flat spring which is attached to the base or supporting structure 12 intermediate its ends by means of the fulcrum supporting pin 24. One end of the resilient mem-

ber 16 is positioned within the notch 30 in flange 26. The notch 30, being substantially the same length as the width of the resilient member 16, functions in cooperation with the fulcrum supporting pin 24 and prevents any movement of the resilient member 16 about the fulcrum pin. Resilient member 16 has a preset downwardly extending arch, as shown in Fig. 5, which, ensures a positive downward biasing action of the free end of such member. The free end thereof will thus be biased towards the base 25 at all times and the movable contact 18 operatively associated therewith will likewise be biased toward the stationary contacts 20.

15 The movable contact 18 comprising a loosely-mounted contact plate 38 is insulatedly attached to the free end of the resilient contact-supporting member 16 by means of an insulated rivet structure 36. The rivet structure 36 is rigidly attached 20 to the free end of the resilient member 16. However, the contact plate 38 is loosely attached to the rivet 36 to ensure positive uniform bridging contact with the stationary contacts 20. It, therefore, follows that as the resilient member 16 is 25 biased downwardly, as hereinabove described, the movable contact 18 operatively associated therewith will likewise be biased downwardly towards the base 25 of the supporting structure 12, and will exert a positive uniform contact pressure on 30 the stationary contacts 20.

The stationary contacts 20 include contact members 40 insulatedly attached to the supporting structure 12. The contact members 40 are, in this instance, strips of an electrical conducting 35 material such as silver surfaced aluminum or copper, which are insulatedly attached to the base 25 by means of rivets 42 and an insulating gasket 44. The contact members 40 of contacts 20 are positioned so that there is a gap located therebetween which is bridged by the movable contact 18 as the resilient member 16 biases or actuates such movable contact into engagement therewith.

If desired, suitable terminals (not shown) may 45 be operatively associated with the contacts 20 to permit the switch to be readily inserted in a circuit to be controlled. However, the stationary contacts 20 may be attached to an appliance, such as a sandwich grill or percolator, by having the 50 conductors thereof directly attached to the contact members 40, as by soldering thereto or in any other desirable manner.

The contact-operating pin or cam roller pin 22 comprises a shaft 23 and a disc-shaped cam or 55 roller 27. The shaft 23 is mounted substantially normal to the base 25 and the resilient member 16, and is journaled in the base 25 at one end thereof and within the resilient member 16 at the other end. The shaft 23 is then free to rotate 60 about the longitudinal axis thereof and also to move longitudinally along such axis because of the length of the shaft. The cam or roller 27 is rigidly positioned upon the shaft 23 intermediate the end thereof, being located between the resilient member 16 and the fan-shaped portion 34 of the operating lever 14.

Therefore, as the operating lever 14 is rotated 70 about the fulcrum pin 24 as an axis, the upwardly extending ledge 35, positioned below the cam 26 of operating pin 22, forces the pin 22 upwardly, this, in turn, forcing the resilient member 16 upwardly. Inasmuch as the pin 22 is journaled within resilient member 16 and base 25, and is mounted substantially normal thereto and to the 75 operating handle 14, such pin will be rotated

about its axis as the operating handle is moved. In addition, the rotation of the operating pin 22 will eliminate or reduce the horizontal component of the force action between the lever 14 and the pin 22 to substantially a minimum value. It, therefore, follows that as the handle 14 is rotated about the fulcrum pin 24, the pin 22 will be moved vertically without any horizontal binding action between the handle 14, the base 25 or the resilient member 16.

The fulcrum-supporting pin structure 24, operatively associated with the operating handle 14 and resilient member 16, as hereinafter described, comprises, in this instance, a one-piece construction including a main body portion 46, a lower sleeve portion 48, an upwardly extending rivet portion 49 and a downwardly extending rivet portion 50 which rigidly attaches the structure to the base 25. The fulcrum pin 24 attaches the operating handle 14 and resilient member 16 to the base in substantially the following manner. The lower sleeve portion 48 of fulcrum pin 24 is inserted through an aperture 56 in the operating lever 14 while the main body portion 46 thereof supports the resilient member 16 above the handle 14, with the upwardly extending rivet portion 49 passing through an aperture 58 in the resilient member 16. The downwardly extending rivet portion 50 is then inserted through the base 25, whereupon the upper and lower ends of rivet portions 49 and 50, respectively, may be spun or riveted over upon resilient member 16 and base 25, respectively, to form a rigid structure. If desired, a washer 60 may be positioned upon resilient member 16 to permit the pin 49 to be spun over thereon without injuring the resilient member 16 in any manner. In addition, a washer or spacer 59 may be positioned on the sleeve portion 48 intermediate the operating lever 14 and the base 25 to space the lever 14 from the base 25.

With the main body portion 46 of fulcrum pin 24 being somewhat larger than the sleeve portion 48, such main body portion will prevent the operating handle 14 from moving vertically along pin 24, while the sleeve 48 will permit the handle to be rotated about such pin as a fulcrum or axis. It is, therefore, obvious that the fulcrum pin 24 rotatably supports the operating handle 14 with respect to the base 25.

The top surface of the main body portion 46 of the fulcrum pin 24 is somewhat below the level of the notch 30 located in flange 26. Accordingly, inasmuch as the resilient member 16 is operatively associated with notch 30 and rigidly attached to the main body portion 46, of pin 24, such member 16 will be held at substantially an angle to the base 25, extending downwardly from the flange 26 to the stationary contacts 20. The pre-arched shape of resilient member 16 then produces a downward biasing action of the free end thereof at all times and, therefore, ensures a positive contact pressure between the movable contact 18, located on the free end of the resilient member 16, and the stationary contacts 20.

It is, therefore, obvious that the operating handle 14, rotatably attached substantially parallel to the base 25, through the cooperative action of operating pin 22, will move the free end of resilient contact supporting member 16 upwardly and will permit it to move downwardly, as the handle is moved from one position to another, to effect engagement and disengagement of the movable contact 18 with the stationary contacts 20.

When operating the appliance switch 10 em- 75

bodying my invention, the operating handle 14 is manually moved substantially in the plane of such operating handle from, say, an "on" position shown in Fig. 3 to an "off" position shown in Fig. 1 or vice versa. The upwardly extending ledge 35 of the fan-shaped portion 34 in the handle 14 then, as the handle 14 is moved from an "on" to an "off" position, forces the operating pin 22 substantially vertically upwards. As the pin 22 is moved vertically along its axis, it forces the free end of the resilient member 16 upwardly against its downwardly biasing action, and, inasmuch as the pin 24 is journaled within the resilient member 16 and base 25, such pin 22 will rotate therein without any binding action therebetween. As the free end of the resilient member 16 is moved upwardly by pin 22, the movable contact 18 operatively associated with the free end thereof, is disengaged from the stationary contacts 20, whereupon the switch is in an inoperative position.

To reengage the contacts 18 and 20, or have the switch returned to an operative position, the operating handle 14 is moved in the opposite direction substantially in its plane, whereupon the upwardly extending ledge 35 is removed from under the pin 22, permitting such pin 22 to rotate and to be vertically moved toward the base 25, by the downward biasing action of resilient member 16. As the ledge 35 is completely removed from under roller 26 of the operating pin 22, the movable contact 18 will again reengage the stationary contacts 20. The downward biasing action of the resilient member 16 thus ensures a positive contact pressure between the cooperating contacts 18 and 20.

It is, therefore, obvious that the switch or circuit interrupter embodying my invention is exceptionally thin and compact, inasmuch as the overall height thereof is substantially determined by the relatively short upwardly extending ledge 26, and that such switch is operated by an operating arm operating in the plane of the switch by moving a contact positioned normal to the plane thereof without any binding action between the cooperating parts.

Various modifications may be made in the device embodying my invention without departing from the spirit and scope thereof, and I desire, therefore, that only such limitations shall be placed thereon as are imposed by the prior art and the appended claims.

I claim as my invention:

1. A circuit interrupter including, in combination, a supporting structure, a plurality of contacts including at least one movable contact and

one stationary contact, a flat inherently resilient member extending over said structure and adapted to insulatedly support the movable contact and to bias it toward the stationary contact, an operating arm pivotally attached to the structure, an operating pin having its ends operatively mounted in the supporting structure and resilient member, respectively, and adapted to move longitudinally along its axis, and means comprising the moving arm for moving the pin along its axis to effect the movement of the movable contact into engagement with or disengagement from the stationary contact.

2. A thin appliance switch including in combination, a supporting base, contact means comprising at least one movable contact, a flat inherently resilient member attached and extending substantially parallel to the base and adapted to insulatedly support the movable contact and to bias it toward the base, an operating pin journaled within the base and the resilient member, said pin being adapted to rotate about an axis normal to the base and to move longitudinally along such axis, a manually swingable operating arm attached substantially parallel to the base and adapted to be moved in its plane, and means comprising a cam surface on the moving arm for engaging an intermediate surface of said pin to convert swinging movement of the operating arm and cam surface to a vertical movement of the pin along its axis in opposition to said flat resilient member.

3. A thin appliance switch comprising in combination, a supporting base including a short upwardly extending flange, contact means comprising at least one movable contact, a resilient member operatively associated with the flange attached to the base and adapted to insulatedly support the movable contact and to bias the contact toward the base, an operating arm rotatably attached to the base and adapted to be moved in its plane, an upwardly extending ledge integral with the arm, an operating pin journaled within the base and the resilient member being adapted to rotate therein, an engageable member positioned intermediate the ends of the pin, said engageable member being operatively associated with the ledge and adapted to convert rotational movement of the operating arm and ledge to a vertical movement along its axis, and means responsive to rotatable movements of the operating arm for vertically moving the pin, resilient member and movable contact substantially normal to the base to effect engagement and disengagement of the contact means.

EARL K. CLARK.
